PROCESS FOR CONCENTRATING AND
STORING OLEFINSRichard F. Robey, Roselle, N. J., assignor to
Standard Oil Development Company, a corpora-
tion of Delaware

Application December 30, 1938, Serial No. 248,472

7 Claims. (Cl. 260—677)

This invention relates to the segregation and storage of olefins and it relates particularly to the separation and storage of the lower olefins, such as ethylene, propylene, butylene, 1,3-butadiene, etc.

The lower olefins are volatile at ordinary room temperatures and upon being heated expand and impart pressures that are proportional to the temperatures. In the storage and transportation of the lower olefins, it has been necessary heretofore to provide tanks or containers of special construction with thick walls and therefore of great weight in order that any substantial large volumes of the olefins may be compressed and stored therein.

An object of this invention is to provide materials in a storage tank to hold the olefins in solution and increase the capacity of the tank.

Another object of this invention is to provide a suitable absorbent material which will hold the olefins in solution or in combination and also separate the olefins from other gases and particularly from other hydrocarbons having the same or approximately the same number of carbon atoms to the molecule.

According to this invention, it has been found that olefins may be separated from other hydrocarbons having similar number of carbon atoms to the molecule by the use of an ammoniacal solution of cuprous benzene sulfonate. This solution is prepared by reacting benzene sulfonic acid with sufficient ammonia to neutralize, adding an excess of free ammonia and saturating the solution with cuprous oxide. It is not necessary that chemically pure benzene sulfonic acid be used. Suitable temperatures for absorbing the olefins in the ammoniacal cuprous benzene sulfonate solutions are from -10° to 25° C. An ammoniacal solution of cuprous benzene sulfonate, on coming into intimate contact with a mixture of olefins and saturated hydrocarbons, dissolves the olefins preferentially and presumably forms an addition compound with the cuprous salt in the solution. The ammoniacal solution of cuprous benzene sulfonate will preferentially extract olefins from a mixture of olefins and saturated hydrocarbons and is recovered from the solution by heating or by reduction of pressure, whereby the dissolved gases effervesce from the solution. Any ammonia in the evolved gases may be removed by scrubbing the gases with water. The gases may be forced into the solution either under ordinary or elevated pressures. At 25° C. and 76 mm. mercury pressure, 1 ml. of the solution absorbs 4.5 ml.

of ethylene and no appreciable volume of ethane.

The solution used contained 3 mols of benzene sulfonic acid with 3 mols of free ammonia per liter and was saturated with cuprous oxide.

The following table gives the solubilities, expressed as the volume of gas (measured under average room conditions) per unit volume of the cuprous solution, for ethylene and propylene in a solution containing 1 mol of benzene sulfonic acid, 3 mols of free ammonia, and 0.69 mol of cuprous oxide. The effects of temperature and partial pressure on the solubility are shown. The saturated hydrocarbons and hydrogen are negligibly (or only very slightly) soluble in these solutions.

Temp., °C.	Gas	Pressure				15
		1 atm.	2 atm.	5 atm.	10 atm.	
30	C_2H_4	1.6	2.5	5.0	7.6	20
20	C_2H_4	0.4	0.8	1.7	3.2	
	C_3H_6	2.8	4.3	7.6	10.1	
10	C_2H_4	0.6	1.2	2.5	4.3	
	C_3H_6	5.3	7.2	10.5	12.5	
0	C_2H_4	1.1	1.9	3.9	6.2	
	C_3H_6	8.5	10.0	12.5	13.8	
	C_4H_8	2.0	3.1	6.0	8.6	25

The saturation limit for olefins in these solutions is dependent upon the concentration of cuprous copper in this solution, since the ethylene combines with the cuprous copper under ideal conditions mol for mol. About 2 mols is the maximum copper content in a typical solution.

As the olefins are soluble to a large extent in the solutions of ammoniacal cuprous benzene sulfonate to form additive compounds, it was found that the addition of these solutions to a tank increases the capacity of the tank for olefins about two-fold in the lower pressure range, that is, 1 to 20 atmospheres pressure. This is best illustrated by reference to the attached drawing of a chart.

The invention is not to be limited to the specific embodiments shown or the specific examples given, nor to any theories advanced as to the operation of the invention, but in the appended claims it is intended to claim all inherent novelty in the invention as broadly as the prior art permits.

I claim:

1. A process for the separation and storage of olefins, which comprises passing through an ammoniacal solution of cuprous benzene sulfonate maintained at a temperature from -10° to 25° C. a normally gaseous mixture containing olefins

and saturated hydrocarbons and separating the unabsorbed saturated hydrocarbons and other insoluble gases.

2. A method of separating olefins from a mixture containing olefins and saturated hydrocarbons, which comprises passing a mixture of normally gaseous olefins and saturated hydrocarbons through an ammoniacal solution of cuprous benzene sulfonate at a temperature from -10° to 25° C., separating the undissolved gases and recovering the olefins from the solution by the application of heat.

3. A method of separating olefins from a mixture containing olefins and saturated hydrocarbons, which comprises passing a mixture of normally gaseous olefins and saturated hydrocarbons through an ammoniacal solution of cuprous benzene sulfonate at a temperature from -10° to 25° C., separating the undissolved gases and recovering the olefins from the solution by lowering the pressure.

4. A method of separating olefins from saturated hydrocarbons, which comprises passing a mixture containing olefins having from 2 to 4 carbon atoms to the molecule through a solution of ammoniacal cuprous benzene sulfonate at a temperature of -10° to 25° C. and at least at-

mospheric pressure, separating saturated hydrocarbons and recovering the olefins from the ammoniacal cuprous benzene sulfonate solution by the application of heat and reducing the pressure.

5. A method of separating ethylene from saturated hydrocarbons having the same number of carbon atoms to the molecule, which comprises passing ethylene at a temperature from -10° to 25° C. through an ammoniacal solution of cuprous benzene sulfonate, separating the saturated hydrocarbons and recovering ethylene by the application of heat.

6. A method of storing olefins, which comprises passing normally gaseous olefins at a temperature from -10° to 25° C. into a storage vessel containing an ammoniacal solution of cuprous benzene sulfonate.

7. A method of storing olefins, which comprises introducing into a container ammoniacal solution of cuprous benzene sulfonate, maintaining the container and its contents at a temperature from -10° to 25° C. and passing normally gaseous olefins that are to be stored into said container under a pressure above atmospheric.

RICHARD F. ROBEY.
